UNITED STATES PATENT OFFICE.

HARRY A. GRINE, OF LOS ANGELES, CALIFORNIA, ASSIGNOR OF ONE-HALF TO FRED C. NELLES, OF LOS ANGELES, CALIFORNIA.

ATOMIZER.

1,156,840.

Specification of Letters Patent. Patented Oct. 12, 1915.

Application filed June 21, 1912. Serial No. 704,949.

To all whom it may concern:

Be it known that I, HARRY A. GRINE, a citizen of the United States, residing at Los Angeles, in the county of Los Angeles and 5 State of California, have invented a certain new and useful Improvement in Atomizers, of which the following is a specification.

My invention relates to a liquid hydrocarbon fuel atomizer, or burner, and has for 10 its object to provide means whereby liquid fuels may be discharged in a thoroughly atomized or broken up condition, and particularly whereby such fuels may be thus discharged into combustion furnaces in connection with the production of heat or gas. The advantage of this atomizer or burner 15 for liquid hydrocarbon fuels over those now in vogue consists in the economy secured by a perfect atomization with low pressure 20 on the steam, air or other elastic fluid medium used in atomizing the liquid hydrocarbon. A pressure of 20 to 25 pounds on the air or steam supply is sufficient when atomizing the very heavy asphaltum base crude 25 oil fuels.

The means for carrying out my invention in a particular form are illustrated in the accompanying drawings, wherein—

Figure 1 is an end view of an atomizer; 30 Fig. 2 a longitudinal vertical section; Fig. 3 is a detail front elevation of the delivery nozzle; Fig. 4 a cross-section through a modified delivery nozzle, and Fig. 5 a cross-section on the line 5—5 of Fig. 2.

Like parts are indicated by the same letters in all the figures.

A is a case having the inward projection A¹ externally screw-threaded at A² to engage corresponding screw threads in an 40 aperture in the chamber wall A³ and internally threaded at A⁴ and provided with the nut A⁵ whereby it may be screwed into the aperture.

B is an oil supply pipe controlled by the 45 valve B¹ and provided with the union B² and screw-threaded into the case so as to connect with the oil chamber B³.

C is a steam pipe controlled by the valve C¹ provided with the union C² and screw 50 threaded into the case so as to connect with the steam chamber C³.

D is an oil pipe screw-threaded to the case at A⁴, and D¹ is an inner smaller steam pipe screw-threaded at D² to the diaphragm in

the case which separates the oil and steam 55 chambers.

E is a mixing chamber shell containing the mixing chamber E¹ and internally screw-threaded at E² to receive the screw-threaded end of the oil pipe D and internally threaded at E³ to receive the threaded end E⁴ of the delivery nozzle.

E⁵ is a plug consisting of three parts, the projection which snugly fits the inside of the pipe D¹ and is secured thereto by brazing, threads, or any other desired manner, the conical end E⁷ which lies within but is smaller than the chamber E⁸ in the mixing chamber shell E and intermediate the portion E⁹ which is square in cross section and fits the inside of the pipe D as indicated in Fig. 5, and is provided with flat sides E¹⁰, E¹¹ between which and the inner walls of the pipe D are a series of passageways from said pipe D to the chamber E⁸. It is provided with the inner passageway E¹¹. The adjustment for the flow of liquid is made by screwing the mixing chamber forward or backward on the threaded end of the pipe D. This opening should be made as small as 80 possible for a required delivery of fluid so as to cause the fluid to pass around the conical end E⁷ of the plug E⁵ in a thin film, thus securing a better mixture with the steam, air or other elastic fluid atomizing agent. 85

The delivery nozzle consists of a body F into which leads a passageway F¹ tangentially. The body is provided with a series of slots F², F³ of any desired size, or shape, or position, but preferably in such a position 90 as to be swept by the current of fluid as it passes along the inside wall of the nozzle.

While it will be evident from what is shown in my drawings that my invention is an operative device, still changes might 95 be made in size, shape and arrangement of parts, without departing materially from the spirit of my invention, and I wish therefore that my drawings be regarded as in a sense diagrammatic.

The use and operation of my invention are as follows: In assembling the parts the mixing chamber shell E is screwed upon the end of the pipe D so that its fluid chamber contains the plug E⁵ and it is brought to a position where a proper annular space remains between the plug and the wall of the fluid chamber. The projection E⁶ closes the end 100 105

of the pipe D¹, the inner passageway of which is therefore connected with the passage E¹¹ in the plug. The middle portion of the plug being irregular in cross section, 5 provides passages connecting the pipe D with the interval between the plug and the walls of the cavity E⁸. Thus the two fluids are brought together in a relatively contracted passage or chamber E¹ where they 10 are mixed and where there is imparted to them a high velocity. I prefer to introduce the steam through the central aperture and oil through the outer annular passageway, having reference to the case where producer 15 gas is to be formed from low-grade oils, but of course other fluids could be used and they could be fed in any desired way with reference to each other. As the mixing fluids under high velocity move forward, they pass 20 the open ends of the narrow slots so that thin films are, so to speak, cut from the passing fluid and discharged through the slots in a highly divided atomized or separated condition. This action is greatly facilitated 25 by the particular forms of nozzle which I have shown wherein the current of mixed fluid passes tangentially around or partly around the inside of the discharge nozzle past the mouths of the slots. As previously suggested, this result could be accomplished 30 by mechanisms greatly varying from those here illustrated.

The mixing nozzle may perhaps more properly be called a supply nozzle, and this term properly includes the end of the two 35 pipes, the plug and the surrounding portion of the connector, the connector for the two nozzles containing a chamber which may be called the mixing chamber. It is also in fact an accelerating chamber. It connects the 40 two nozzles.

I claim:

1. An atomizer head comprising a substantially circular drum, a supply pipe therefor projecting tangentially thereinto 45 beyond the center thereof and discharging against the curved circular wall, a spray discharge outlet located in said circular wall in the path of the fluid leaving the supply pipe.

2. An atomizer head comprising a substantially circular drum, a supply pipe therefor projecting tangentially thereinto beyond the center thereof and discharging 50 against the curved circular wall, a spray discharge outlet slot, said slot extending transversely across the path of the material leaving the supply pipe.

Signed at Seymour, Mo., U. S. A., this 17 day of June, 1912.

HARRY A. GRINE.
